The ornamental design for a pool, as shown and described.

DESCRIPTION

FIG. 1 is a perspective view of a first embodiment of a pool showing the design;

FIG. 2 is a top view of the embodiment shown in FIG. 1; FIG. 3 is a front view of the embodiment shown in FIG. 1; FIG. 4 is a rear view of the embodiment shown in FIG. 1; FIG. 5 is a bottom view of the embodiment shown in FIG. 1;

FIG. 6 is a left end view of the embodiment shown in FIG. 1;

FIG. 7 is a right end view of the embodiment shown in FIG. 1;

FIG. 8 is a perspective view of a second embodiment of a pool showing the design, the second embodiment being generally the same as the first embodiment but having a removable divider; and,

FIG. 9 is a top view of the embodiment shown in FIG. 8. The subject matter shown in broken lines forms no part of the claimed design. The stippled surfaces indicate surface treatment, namely a sprayfoam coating that is applied to the metal of the shipping container from which the pool is made.
